UNITED STATES PATENT OFFICE.

ROBERT GOOD, OF WASHINGTON, PENNSYLVANIA, ASSIGNOR TO HAZEL-ATLAS GLASS CO., OF WHEELING, WEST VIRGINIA, A CORPORATION OF WEST VIRGINIA.

ROTARY VERTICAL LEER.

Application filed April 28, 1924. Serial No. 709,596.

This invention relates to leers for annealing glassware, and particularly to a series of vertical tubular leers through which the glassware slowly travels from top to bottom, the glassware being gradually cooled during its passage. In the present embodiment of the invention a number of such vertical leers are arranged in a circular series, and the series as a whole is given a rotary motion while the articles are being slowly carried step by step from top to bottom of the leers.

The objects and advantages of the invention will be apparent from the following detailed description when considered in connection with the accompanying drawings, in which:

Figure 1 is a vertical sectional view of the apparatus, parts being omitted and parts being broken away for the sake of clearness.

Figure 2 is a plan view of the apparatus; parts being broken away to more clearly show the construction.

Figure 3 is a detail vertical sectional view of the upper portions of a number of the leers; and

Figure 4 is a detail vertical sectional view of the lower portion of one of the leers, and showing the means for preventing the admission of air to the bottom of the leer.

Before describing the apparatus as a whole I shall first describe one of the single ovens or leers which are united in a circular series to form the complete apparatus. Each of the single ovens forming the apparatus is substantially identical in construction with the leer disclosed in my application Serial No. 709,595, filed April 28, 1924.

Referring particularly to Figure 1, it will be noted that the bottom portion of the leer of that figure has been omitted; and that in the leer on the left of that figure the central portion has been broken away in order that the bottom portion of the leer may be shown.

Numeral 1 indicates a muffle or oven, the passage through which is preferably cylindrical, as indicated by numeral 2. The muffle may be manufactured of any desired

material, such as carbofrax, and in the preferred construction each of the carbofrax blocks forming the muffle will be provided with a semi-cylindrical passage adapted to align with a similar passage in the adjacent block, thereby forming a cylindrical passage when the blocks are assembled. Obviously, however, the muffle may be constructed in any desired manner.

Also provided in the muffle blocks is a burner passage 3 shown in plan in Figure 2, and arranged in this passage is a burner 4 comprising a tube provided with a plurality of jet holes. I have illustrated two of the burners, but any number may be employed, and by the selective use of them the effective length of the muffle may be varied. Any suitable means may be provided for furnishing air to the burners, such as passages communicating with the atmosphere and having control dampers 5.

The length of the muffle will vary in accordance with the height of the ware and the speed with which the articles are carried therethrough, though it will be understood that the length may be varied within very wide limits, as conditions warrant. And in place of actually varying the length of the muffle, the effective length thereof may be varied as above described. Arranged below the muffle is a tubular member of heat-absorbing material, such as ordinary fire clay or other refractory material, as indicated by numeral 6. This heat-absorbing member becomes saturated with heat, furnishing substantially a fireless extension of the muffle, and its length also is governed by the height of the ware and the speed with which the articles are carried therethrough. While I have specifically described this section of the leer as formed of heat-absorbing material, it will be understood that the invention is in no manner limited to a leer having the heat-absorbing section, and in place of the heat-absorbing material I may employ any desired non-heat-absorbing material.

Arranged below the heat-absorbing member is a sheet metal member 7 which extends all the way from the bottom of the heat-absorbing member 6 to the bottom of

the leer, which may be ten or fifteen feet, or any length desired.

Each of the ovens or leers is inclosed in a casing of insulating material, such as silo-cel, as indicated by numeral 8; and provided in the casing of insulating material is a passage 9 extending from the top to the bottom of the construction, there being one of these passages for each leer, and arranged 10 within this passage is one run of an endless chain or belt 10. The endless chain passes over an idler at the bottom of the leer and over a holding sprocket 11 at the top of the leer. Obviously, the sprocket may be permitted 15 to rotate intermittently in any desired manner; but I have illustrated herein a rotatable shaft 12 carrying a worm 13 engaging a worm wheel 14 fixed on the sprocket shaft. The means for intermittently 20 rotating the shaft 12 to permit the rotation of the sprocket 11, will be described hereinafter.

A number of flights or shelves 15 are attached to the endless chain at regular intervals, and these shelves project into the tubular oven through a slot 16 extending from the top to the bottom of the oven. Attached to each of the flights is a relatively narrow plate 17, and these plates pass down 30 through the passage 9 and cover the slot 16. An inspection of Figure 1 will show that the ends of adjacent plates are oppositely beveled so that they will overlap, thereby constituting means for preventing the entrance 35 and exit of air to and from the leer through the slot 16. While I have illustrated the plates with oppositely beveled ends, it will be understood that any overlapping construction of the plates may be employed. 40 These plates possess the further function of bracing and adding rigidity to the conveyer flights.

The bottom of each of the tubular ovens and the bottom of each of the passages 9 are 45 provided with a pair of tiltable closure members 18, which extend entirely across the bottom of each leer and passage 9, and which are normally held in closed position by means of counterweights 19, thereby preventing 50 to a large extent the entrance of air to the leer. The specific structure here described does not form an essential feature of the invention, and obviously any means for accomplishing the same purpose may be 55 employed.

Positioned below the leer is a chute 20 into which the glassware falls after having been annealed, and it is delivered by the chute to an endless belt 21 which conveys the ware 60 to any desired point.

The operation of a single leer will now be described.

At the completion of the manufacturing process the articles, while still retaining 65 their residual heat, are placed on the endless

conveyer by an attendant or by automatic machinery. It will be understood, of course, that if the residual heat is not sufficient for the annealing operation, such additional heat as may be necessary will be furnished in the muffle. It is found that very little, if any, additional heat will be necessary, as will appear hereafter. As each article is placed on a conveyer shelf the endless conveyer is moved one step, in a manner to be described hereinafter, to carry the article within the muffle. This operation is continued step by step until the articles are carried the full length of the leer and are delivered through the chute 20 to the conveyer 21.

Each hot article that is placed in the leer has beneath it another article at only a slightly lower temperature than itself, and the heat that is radiated from this lower body functions as a baffle or barrier to prevent the rapid radiation of heat from the upper article. While I have simply mentioned the article directly beneath the article last introduced, it will be obvious that there 90 is a whole series of articles below the uppermost article, and each one of this series functions in the same manner to reduce radiation from the uppermost article; though, of course, the articles further removed from the uppermost article do not exert this influence to the same extent as does the article immediately beneath it. It will also be understood, of course, that, while all of the heated articles below the uppermost article 95 tend to prevent radiation of heat from that article, so, too, is radiation of heat from lower articles retarded by the articles below them which have a temperature only slightly lower.

It will also be understood that as the articles are introduced at the top of the leer in a heated condition, and slowly move downwardly through the chamber, after passing through the muffle, the contents of the chamber will give up their heat gradually as they move down and the air thus heated will rise to the top of the leer, thereby contributing to the maintenance of the 100 temperature of the upper portion of the 115 chamber.

In order to properly anneal glassware, the articles should be gradually cooled from about 950° to about 600°; and from the foregoing description it will be apparent that the temperature of the leer disclosed herein will naturally be the highest at the top of the leer, and that this temperature will be decreased very gradually toward the bottom of the leer.

It will also be apparent that in annealing glassware in the manner described herein very little, if any, heat other than the residual heat of the articles is necessary. If the articles were introduced at the bottom 130

of the leer and were carried upward, the heat given off by the articles would rise to the top of the leer and consequently the articles would be discharged from the leer 5 at substantially the same temperature at which they entered. And it is also true that if a horizontal leer were employed the operation would be by no means the same, for there would not be the same even distribution of heat at a gradually lowering temperature; and, further, it would be necessary to supply a large amount of heat to the leer, for the horizontal leer does not present the same economical arrangement 10 as this vertical leer wherein the heat given off by the articles being annealed rises to the top to maintain the temperature of the upper portion of the leer.

Having fully described the construction 20 and operation of a single leer, I will now proceed to describe the construction and operation of the complete apparatus.

Any number of the individual leers may be grouped in a circular series, and in the 25 present instance I have illustrated twenty-eight of them inclosed in an outer and inner casing of insulation material 8. For purposes of description this large circular member containing the twenty-eight individual 30 ovens will be termed the rotary leer.

The apparatus may, of course, be installed in any desired manner, but it is preferred to have the lower portion thereof arranged in a cellar, or the like, while the upper portion 35 thereof projects up above the floor indicated by numeral 22. By the arrangement clearly illustrated in Figure 1, an attendant may stand on the floor 22 and be in a position to place the glassware in the top of the leer, in the event that the glassware is fed by 40 hand.

The base of the apparatus is indicated by numeral 23, and mounted in this base 45 and extending upwardly to the top of the apparatus is a fixed column 24. The upper end of this column is mounted in a frame 25 supported from the floor. Adjacent its upper end the column 24 is provided with a collar 26 having a ball-bearing race on 50 which is mounted a large circular plate 27. This plate is of substantially the same size as the cross sectional area of the rotary leer, and rods 28 are connected to the plate and to the leer to support the latter. A spider frame 29 is mounted on a ball-bearing race 55 provided in the base 23, and this spider carries a plurality of upwardly extending arms 30 which, in conjunction with the rods 28, support the rotary leer. It will thus be seen 60 that the apparatus as a whole is mounted to freely rotate on the column 24. Obviously, any desired means may be employed to rotate the leer, but in the preferred construction illustrated herein the periphery 65 of the plate 27 is provided with gear teeth

31; and these teeth are engaged by a pinion 32 driven by a motor 33. The invention is not limited, of course, to any particular means for rotating the leer, and it may be rotated continuously or intermittently by 70 motor or by any other driving means; and, if desired, the rotary leer may be driven by, and synchronized with, any conventional glass-making machine.

Each of the individual ovens is provided 75 with the endless conveyer 10, and with a holding sprocket 11; the sprocket being rotated by the weight of the ware on the downward run of the conveyer, and being permitted to rotate at intervals by the rotation of the shaft 12 carrying a worm 13 which engages the worm wheel 14. Various means may be employed for intermittently rotating the shaft 12; but in the preferred construction a fixed toothed segment 34 is 80 so positioned as to be engaged by the pinions 35 fixed to the shafts 12. The rack 34 will be of such length that each pinion 35, as it is brought into engagement with the rack, will be rotated sufficiently to permit the 85 conveyer to move one step downwardly, thus carrying the glassware into the top of the leer.

Gas may be supplied to the burners in any 90 desired manner, but for the purposes of illustration I have shown a pipe 36 leading to a central recess 37 in the base of the fixed column 24. A manifold 38 surrounds the column and pipes 39 lead radially from the manifold to the various burners 4. Various 100 other methods of supplying the gas could be employed; and it will be understood that, if preferred, the column 24 could rotate with the leer, and in such a construction the pipes 39 could be connected directly to the passage 105 37 in the column, thereby eliminating the manifold 38.

While I have illustrated and described 110 burners for supplying additional heat to the leer, it is to be understood that the burners may be eliminated and the annealing operation accomplished solely by the residual heat of the articles. The operation of the leer without the use of a burner is described in my application Serial No. 709,595, filed 115 April 28, 1924, hereinbefore mentioned, and for a full description of such a leer reference is to be had to that application.

It is believed that the operation of the 120 rotary vertical leer will be fully understood from the foregoing description, but it may be briefly described as follows:

Assuming that the feeding station is located at the left of Figure 1; as each oven 125 with its conveyer and operating mechanism approaches this station, the pinion 35 of that particular oven will engage the fixed toothed segment 34 and the conveyer thus be permitted to move down one step carrying into the top of the leer the glassware 130

that has been placed on the conveyer. As this article is moved into the top of the leer the lowermost article is discharged from the bottom of the leer into the chute 20 and 5 thence to the endless belt 21. The rotary leer continues its rotation and the article that was moved into the top of the oven, as well as all other articles in the oven, remains in its same vertical position until the leer 10 has made a complete rotation. At the end of a complete rotation the article is moved down one more step and retains that vertical position until another complete rotation has been made, whereupon it is moved down one 15 step farther, and so on until the article, completely annealed, is discharged from the bottom of the leer. The operation of all of the individual ovens is exactly the same; each oven as it approaches the feeding station 20 receiving an article to be annealed, and at the same time discharging an annealed article; and all of the articles retain their vertical position in the rotary leer during a complete rotation thereof until they approach the feeding station.

It will be understood, of course, that the articles may be placed on the shelves of the endless conveyer by hand or by any desired automatic machinery; and the leer may be 30 rotated continuously or intermittently, and it may be synchronized with a glass machine.

In accordance with the patent statutes, I have described what I now believe to be the 35 best embodiment of the invention, but I do not wish to be understood thereby as limiting myself or the scope of the invention, as many changes and modifications may be made without departing from the spirit of 40 the invention; all such I aim to include in the scope of the appended claims.

Having thus described the invention, what I claim as new and desire to secure by Letters Patent is:

- 45 1. A revolute vertical leer for annealing glassware, and means for carrying glassware through the leer.
2. A rotary leer for annealing glassware, and means for carrying glassware downwardly through said leer.
- 50 3. A rotary leer for annealing glassware, an oven extending vertically therethrough, means for rotating the leer, and means for carrying glassware downwardly through the oven.
- 55 4. A rotary leer for annealing glassware, means for rotating the leer, and a plurality of conveyers for carrying glassware downwardly through the leer.
- 60 5. A rotary leer for annealing glassware, a plurality of separate vertically arranged ovens provided in the leer, and means to carry glassware through the ovens.
- 65 6. A rotary leer for annealing glassware, a plurality of separate vertically arranged

ovens provided in the leer, and an endless conveyer passing downwardly through each oven.

7. A rotary leer for annealing glassware, a plurality of separate vertically arranged 70 ovens provided in the leer, an endless conveyer passing downwardly through each oven, and means for operating said conveyer intermittently.

8. A rotary leer for annealing glassware, 75 an oven extending vertically therethrough, an endless conveyer passing downwardly through the oven, and means for operating said conveyer in a certain position of the rotary leer.

80 9. A rotary leer for annealing glassware, an oven extending vertically therethrough, an endless conveyer passing downwardly through the oven, and means for intermittently operating the conveyer.

85 10. A rotary leer for annealing glassware, an oven extending vertically therethrough, a conveyer for carrying glassware downwardly through the oven, and means for moving said conveyer one step during a 90 complete revolution of the rotary leer.

95 11. A rotary leer for annealing glassware, a plurality of ovens extending vertically therethrough, an endless conveyer mounted in each oven, and means for moving each of 95 said conveyers one step during a complete revolution of the rotary leer.

12. A rotary leer for annealing glassware, means for rotating the leer, and means for moving each article downwardly one step 100 in the leer during a complete rotation thereof.

13. A rotary leer for annealing glassware, an oven extending vertically therethrough, means for moving glassware into the leer in 105 one position of the latter, and means for discharging glassware in the same position of the leer.

14. A rotary leer for annealing glassware, a plurality of ovens extending vertically 110 therethrough, an endless conveyer for each oven, and means for automatically operating each conveyer at a predetermined position of the rotary leer.

15. A rotary leer for annealing glassware, 115 a plurality of ovens extending vertically therethrough, an endless conveyer for each oven, a holding sprocket for each conveyer, a pinion operatively connected with each holding sprocket, and means for rotating the 120 pinion during the rotation of the leer.

16. A rotary leer for annealing glassware, a plurality of ovens extending vertically therethrough, an endless conveyer for each oven, a holding sprocket for each conveyer, 125 a pinion operatively connected with each holding sprocket, and a fixed toothed segment adapted to be successively engaged by each pinion.

17. A rotary leer for annealing glassware, 130

a plurality of ovens extending vertically therethrough, an endless conveyer for each oven, a rotary plate supporting said leer, means for rotating said plate, a plurality of rotatable shafts mounted in said rotatable plate and connected with the conveyer, a pinion carried by each rotatable shaft, and a fixed toothed segment adapted to be engaged successively by said pinions.

18. A rotary vertical leer for annealing 10 glassware, and means for carrying glassware longitudinally through the leer.

ROBERT GOOD.
